United States Patent Office

Des. 176,839
Patented Feb. 7, 1956

176,839

AIRPLANE

Willard R. Custer, Hagerstown, Md.

Application August 2, 1955, Serial No. 37,284

Term of patent 14 years

(Cl. D71—1)

F I G. 1.

F I G. 2.

FIG. 3.

FIG. 4.

Figure 1 is a perspective view of an airplane embodying my new design;

Figure 2 is a front elevation of the design;

Figure 3 is a top plan view of the design; and

Figure 4 is a side elevation of the design.

The essential features of my design reside in the portions shown in full lines.

I claim:

The ornamental design for an airplane, as shown and described.
